FIG.5

FIG.6

FIG. 7.

FIG. 1 is a front elevational view of a combined portable phonograph and radio, showing my new design;

FIG. 2 is a side elevational view looking from the left of FIG. 1;

FIG. 3 is a rear elevational view;

FIG. 4 is a side elevational view looking from the right of FIG. 1;

FIG. 5 is an elevational view of the inside of the cover;

FIG. 6 is a plan view of the turntable and radio portion; and

FIG. 7 is a top perspective view showing the turntable and radio as seen in FIG. 6, and the cover as seen in FIG. 5.

The dominant features of my design reside in the portion shown in full lines.

I claim:

The ornamental design for combined portable phonograph and radio, as shown and described.
